ALKYLATION PROCESS AND STABILIZATION
OF PRODUCTLe Roi E. Hutchings, Crystal Lake, Ill., assignor to The
Pure Oil Company, Chicago, Ill., a corporation of Ohio
Filed Aug. 21, 1961, Ser. No. 132,912
9 Claims. (Cl. 260—683.61)

This invention is directed to the manufacture of paraffinic hydrocarbons boiling in the range of about 49° C. to about 100° C. at 760 mm. Hg, i.e., in the hexane and heptane boiling range, which paraffinic hydrocarbons have a low content of benzene and other aromatic hydrocarbons. More particularly, this invention relates to a method of preparing hexane or hexane-containing fractions (commercial hexane), or C₆—C₈ hydrocarbon fractions of low benzene (or other aromatic hydrocarbon) content, by conventionally reforming a naphtha rich in C₆—C₈ hydrocarbons, stabilizing the reformat, subjecting the stabilized reformat to conventional solvent extraction to separate an aromatic-rich extract and a paraffin-rich raffinate (containing the paraffins and predominating in hexanes), subjecting the raffinate to alkylation, and fractionating the resulting alkylate to separate a fraction rich in said paraffins, i.e., hexane which has a concentration of aromatics less than about 0.5% by volume. This invention is also directed to preparing heptane or heptane-containing fractions (commercial heptane) containing low concentrations of toluene by the foregoing steps and separating a heptane fraction boiling in the range of 75° C. to about 100° C. which is substantially free of toluene (contains less than 0.5% toluene) and to the treatment of a reformat to produce a 49° C.—100° C. fraction, by said steps, from which is produced both a hexane fraction and a heptane fraction, free of benzene and toluene respectively, which qualify as commercial hexane and heptane fractions. This invention is directed particularly to the preparation of substantially pure alkanes, boiling in the range 49° C. to 75° C. at 760 mm. Hg.

Hexane and hexane fractions are used commercially as solvents and as raw materials for the manufacture of various chemicals. They frequently are obtained by fractional distillation from petroleum streams which also contain benzene. In general, it has been economically possible to obtain hexane fractions containing as little as about 2% v. of benzene by extraction and distillation, but the relatively close boiling points of benzene and hexane have made more complete separation than this impossible. Although hexanes containing more than about 2.0% v. of benzene still are widely marketed, there are indications that the future specification for maximum benzene content in hexanes may be set at 0.5% v. In any event, hexanes containing less than about 0.5% v. of benzene usually can command a higher market price than hexanes containing greater amounts of benzene. The same considerations apply to heptane fractions and their toluene content.

Now, in accordance with this invention, I have devised an integrated process for the preparation of paraffinic hydrocarbon fractions, such as hexanes, containing not more than 0.5% v. of benzene from a naphtha rich in hydrocarbons containing 6 to 8 carbon atoms per molecule. I have also devised an integrated process for the preparation of paraffinic hydrocarbon fractions, such as heptanes, containing no more than about 0.5% v. of toluene from a naphtha rich in hydrocarbons containing 6 to 8 carbon atoms per molecule.

The process of this invention consists of the steps of (1) catalytically reforming a naphtha rich in hydrocarbons containing 6 to 8 carbon atoms per molecule, (2) subjecting the effluent from the reforming operation to extraction by contact with a selective solvent for aromat-

2

ics, (3) if hydrocarbons of over 8 carbon atoms are present, distilling to recover the desired hydrocarbon fraction in the range C₆—C₈, this step may be carried out prior to extraction, (4) combining the selected raffinate fraction (i.e., the paraffin-rich fraction) from the extraction step with an alkylatable hydrocarbon mixture, such as isobutane and isobutylene, (5) subjecting the mixture to contact with hydrofluoric or sulfuric acid under alkylation conditions, and (6) fractionally distilling the effluent from the alkylation reaction to obtain alkylate, unreacted paraffins, (that is, the isobutane and isobutylene), and a C₆—C₈ hydrocarbon fraction, i.e., a hexane fraction containing less than 0.5% v. of benzene or a heptane fraction containing less than 0.5% v. of toluene, or to obtain both such fractions from a given reformat.

Accordingly, it becomes a primary object of this invention to provide a process for preparing substantially aromatic-free C₆—C₈ paraffins.

Another object of this invention is to provide a process for preparing commercial hexane having a content of benzene of less than about 0.5% by volume.

A further object of this invention is to provide a process for preparing commercial heptane having a content of toluene of less than about 0.5% by volume.

An object of this invention is to provide a process for preparing substantially aromatic-free commercial hexane which comprises catalytically reforming a naphtha, stabilizing the reformat, subjecting the reformat to extraction to recover a raffinate rich in paraffinic hydrocarbons, combining the paraffin-rich fraction with an iso-paraffinic hydrocarbon and an olefin, subjecting the mixture to acid alkylation, and fractionating the alkylate to recover a fraction consisting of hexane containing less than about 0.5% by volume of benzene.

These and other objects of this invention will be described or become apparent as the specification proceeds.

The drawing is a diagrammatic illustration of the process steps of the invention. Valves, pumps, heat exchangers and other auxiliary equipment which will be obvious to one skilled in this art have been omitted for simplicity.

Naphtha, rich in hydrocarbons containing six carbon atoms per molecule (paraffins and naphthenes), enters through line 10 and flows to catalytic reforming unit 12. Gaseous products are removed from the reformed product (stabilization of the reformat) to prevent their interference with subsequent extraction. This is accomplished by sending the reformat through line 14 to still 16 wherein gaseous products are taken overhead at line 18. Any hydrocarbons above C₈ are taken off as bottoms at line 20. The stabilized and selected product from reforming unit 12 flows through line 22 to extraction tower 24, wherein it is countercurrently contacted with selective solvent entering through line 26. Rich solvent from tower 24, containing dissolved aromatics, flows through line 28 to stripping tower or still 30, from which aromatics are withdrawn as product through line 32, while lean solvent is withdrawn through line 26 and recycled to extraction tower 24.

Raffinate from extraction tower 24 flows through line 34 and joins paraffinic hydrocarbon (isobutane) entering through line 36 and olefinic hydrocarbon (isobutylene) entering through line 38.

The mixture then flows through line 40 to alkylation reactor 42, where it is contacted at alkylation conditions with hydrofluoric or sulfuric acid entering through line 44. Here any benzene is alkylated by a portion of the isobutylene to produce a higher-boiling product during the alkylation of isobutane by isobutylene. Spent acid is withdrawn from alkylation reactor 42 through line 46, while the alkylated hydrocarbon mixture is withdrawn through line 48, and transferred to fractional distillation

tower 50. Alkylate is withdrawn from tower 50 through line 52, and an aromatic-free naphtha (hexane or heptane) fraction containing less than 0.5% v. of benzene or toluene, respectively, is withdrawn through side-stream 54. Unreacted alkylatable hydrocarbons (isobutane and isobutylene) are withdrawn through line 56 and recycled to alkylation reactor 42 via line 40.

In order to illustrate the invention, the following examples are given.

EXAMPLE I

A sample of raffinate obtained by selectively extracting aromatics from a catalytic reformate (Udex raffinate from Platformer product) was used along with isobutane and isobutylene in an alkylation run with liquid hydrofluoric acid as catalyst, to determine whether this treatment would lower the benzene content of the raffinate. Another portion of the raffinate was used in an alkylation run with 98% sulfuric acid as the catalyst. The details and results of the alkylation runs were as follows:

Isobutane-Isobutylene Alkylation in the Presence of Udex Raffinate

[Properties of Udex Raffinate: Gravity 74.8° A.P.I.; A.S.T.M. Distillation (° F.); IBP 130, 5% 150, 10% 154, 30% 161, 50% 169, 90% 195, E.P. 221]

Run No.	Catalyst	Reactants						Conditions		Product		
		Udex Raffinate		Isobutane		Isobutylene		Temp. (° F.)	Press. (mm.)	Total Yield (g.)	Benzene Content (Vol. percent)	Calculated Max. Benz. Content of Hexane Cut, (Vol. percent)
		g.	moles	g.	moles	g.	moles					
1-----	Liq. Hydrofluoric Acid (40 g.)	131.5	1.4	47	0.8	45	0.8	1125	-----	214	0.14	0.50
2-----	98% Sulfuric Acid (400 g.)	361	4.0	70	1.2	56	1.0	214-32	atm.	approx. 470	0.13	0.38

¹ Heated in closed steel bomb for 5 hours.

² Stirred for 1.5 hours.

The "Calculated Maximum Benzene Content (vol. %) of the Hexane Cut From Alkylation Product" was determined on the assumption that the hexane distilled from the alkylation products would contain all of the benzene present. Thus, these values represent the maximum possible benzene concentration in the hexane. In practice, the values probably would be smaller.

It previously had been determined that precise distillation of this raffinate would yield 44.1% v. of hexane containing 2% v. of benzene. Thus, it is apparent that the alkylation carried out in accordance with this invention resulted in a markedly superior product.

EXAMPLE II

A sample of raffinate boiling up to 440° F. (227° C.), and obtained by selectively extracting aromatics from a Platformer product with diethylene glycol, is fractionally distilled to obtain 6.1% of a C₆-C₈ hydrocarbon fraction containing 2.1% benzene. A mixture of 150 cc. of this C₆-C₈ fraction and 100 cc. of 98% sulfuric acid is stirred under atmospheric pressure at 40° F. (4.5° C.) while a mixture of equal volumes of isobutane and isobutylene is passed therethrough. While the normal alkylation reaction is occurring with isobutane and isobutylene, much of the benzene in the C₆-C₈ fraction is being alkylated by isobutylene to give alkyl aromatic material boiling much higher than hexane. The 310 cc. of hydrocarbon product resulting from the alkylation is fractionally distilled to give 38 cc. of a hexane product boiling between 65° C. and 75° C. at 760 mm. and containing 0.24% benzene. This final product is suitable for use as commercial hexane.

EXAMPLE III

A sample of raffinate boiling up to 228° C., obtained by selectively extracting aromatics from a Platformer

product with 2-hydroxyethyl dimethyl carbamate, is fractionally distilled to obtain about 6.5% of a C₆-C₈ hydrocarbon fraction predominating in heptane containing about 2.1% of aromatics, principally toluene. A mixture of about 150 cc. of this C₆-C₈ fraction and 100 cc. of 98% sulfuric acid is stirred under atmospheric pressure at about 5° C. while a mixture of equal volumes of isobutane and isobutylene is passed therethrough. While the normal alkylation reaction between the isobutane and isobutylene is progressing, the aromatic content of the mixture is being alkylated by isobutylene to toluene and other alkyl aromatics boiling higher than heptane. The 320 cc. hydrocarbon product resulting from the alkylation is fractionally distilled to give about 38 cc. of a heptane-fraction product boiling between 90°-100° C. at 760 mm. and containing about 0.24% toluene. This final product is suitable for use as commercial heptane.

EXAMPLE IV

A sample of raffinate boiling up to 230° C., obtained

by selectively extracting aromatics from a Platformer product with 2-hydroxyethyl dimethyl carbamate containing about 5% of water, is fractionally distilled to obtain about 7.0% of a C₆-C₈ hydrocarbon fraction containing about 1.4% toluene and 0.7% benzene. A mixture of 150 cc. of this C₆-C₈ fraction and 100 cc. of hydrofluoric acid is stirred under atmospheric pressure at about -10° C. while a mixture of equal volumes of isobutane and isobutylene is passed therethrough. Here again, while the normal alkylation reaction is occurring between isobutane and isobutylene, much of the benzene in the C₆-C₈ fraction is being alkylated by isobutylene and portions of the toluene are being alkylated to alkyl aromatic hydrocarbons boiling much higher than the hexane and heptane. The 300 cc. of hydrocarbon product resulting from the alkylation is fractionally distilled to give about 15 cc. of hexane fraction boiling between 65° C. and 75° C. at 760 mm. and containing 0.11% benzene as one fraction and about 18 cc. of a heptane fraction boiling between about 75° C. to 100° C. at 760 mm. and containing 0.13% toluene. These final fractions are suitable for use as commercial hexane and commercial heptane fractions, respectively.

The reforming operations taking place in reformer 12 are conventional. Various catalytic reforming operations and processes are suitably employed in the practice of this invention. Suitable reforming processes may be sufficiently described and identified to those skilled in the art by their descriptive names which are generally known and used and licensed throughout the petroleum industry. Accordingly, catalytic reforming processes applicable in the practice of this invention include, but are not limited to Catforming, Catalytic Reforming, Houdriforming, Ultraforming, Platforming, Cycloversion, Fixed Bed Hydroforming, Fluid Hydroforming, Hyperforming, Thermo-

for Catalytic Reforming, or Savaforming and the like. These catalytic processes are generally and specifically described in the literature and patents relative thereto. These catalytic processes have as their objectives the upgrading of relatively low-grade or low-octane naphthas or petroleum fractions in the gasoline boiling range, or naphthas generally, to higher-octane motor gasolines. Such a product is removed from the instant process at lines 14 and 20. These processes also have as their objectives the production of high-octane motor-fuel components from naphthas or selected petroleum fractions, or the production of high yields of aromatics, petrochemicals, or high-quality motor-fuel components. Such a product or products are removed from either lines 32 or 14 in the instant process and do not constitute the primary objective of this invention. In these processes the separation of components, particularly by solvent extraction, produces a predominantly paraffinic product which is the primary source of the C₆-C₈ paraffinic product of this invention.

The catalytic reforming reaction taking place in reformer 12 may be carried out by employing a fixed bed of catalyst, a moving bed of catalyst, a catalyst in fluidized condition, or any of the various combinations of these processes carried out in a single reaction zone or a plurality of reaction zones. The conditions of operation are well known. The temperature may range from about 700° F. to 1050° F. and preferably is about 850-1000° F., and the pressure may vary from about 150 to 1000 p.s.i.g., with 200 to 750 p.s.i.g. preferred, depending on the severity of reforming desired and on the composition of the naphtha charge entering at line 10.

The numerous catalyst compositions known in the art to attain these objectives may be used, e.g., chromia-alumina catalysts, platinum-containing catalysts, molybdena-alumina catalysts, and cobalt molybdate catalysts. Cycloversion over bauxite at 950-1000° F. and 50-60 p.s.i.g., Hydroforming over MoO₃/Al₂O₃ at 900° F. and 150 p.s.i.g., Platforming over Pt/Al₂O₃ at 900° F. and 750 p.s.i.g., Fluid Hydroforming over MoO₃/Al₂O₃ at 890-940° F. and 200 p.s.i.g., and Ultraforming over Pt/Al₂O₃ at 900-950° F. and 200-500 p.s.i.g. are non-limiting examples. The foregoing processes mentioned generally or specifically simultaneously accomplish to various degrees such reactions as aromatization or dehydrocyclization, dehydrogenation, isomerization, disproportionation along with some cracking taking place depending on the severity of the treatment and the nature of the naphtha feed. Dehydrogenation converts naphthenic hydrocarbons to aromatics, and isomerization converts n-paraffinic hydrocarbons to isoparaffinic hydrocarbons; these are further converted to the corresponding aromatic hydrocarbons. A preferred reforming catalyst comprises platinum or palladium supported on alumina or on a siliceous cracking catalyst. Such catalysts are well-known in this art and contain about 0.1 to 1.0% by weight of platinum or palladium on the selected support. These catalysts and their preparation are described in a number of U.S. patents, e.g., 2,705,329; 2,589,189; 2,550,531; 2,479,109, and 2,478,916. About 0.1 to 0.8% of fluorine or chlorine as combined halogen based on the support may be incorporated, if desired. The manner of preparation is in accordance with conventional techniques of impregnation of the selected support, e.g., alumina, silica-alumina, silica-zirconia, silica-alumina-zirconia, etc., with an aqueous solution of chloroplatinic acid or chloropalladic acid, or with an aqueous solution of the ammonium salts of these acids. After impregnation, the support is dried at about 210° to 250° F. and reduced with hydrogen at about 200°-300° F.

Following the catalytic reforming operation, the resulting liquid reformate in line 14 is subjected to some form of separation, i.e., by absorption, solvent extraction, etc., to separate a predominantly aromatic fraction at line 32 and a predominantly paraffinic fraction at line

34. The preferred method of separation is by means of solvent extraction, i.e., liquid-liquid contact with a selective solvent which selectively dissolves the aromatic hydrocarbons and leaves an undissolved raffinate of paraffinic hydrocarbons. The raffinate in line 34 is subjected to washing or distillation to remove the small portions of solvent, prior to entry into line 40. Thus the raffinate may be sent through a still and a solvent-free raffinate produced, which is sent to line 40. Since this treatment is well-known, it is not shown in the drawing. In some instances, where the solvent is inert, present in very small quantities, and is not affected by the alkylation reaction, solvent separation from the raffinate is unnecessary.

Selective solvents suitable for use in extraction tower 16 include the well-known selective solvents for aromatics, e.g., diethylene glycol, triethylene glycol, tetraethylene glycol, monopropylene glycol, dipropylene glycol, tripropylene glycol, mono-, di- and tri-butylene glycols, phenol, sulfur dioxide, nitrobenzene, furfural, Chlorex, 2-hydroxyethyl dimethyl carbamate, and others. Also suitable as selective solvents are the polyoxypoly-alkylene glycols, the glycol ethers, such as the Cellosolve series of compounds, alkyl ethers of ethylene glycol, including methyl-Cellosolve, ethyl-Cellosolve, propyl-Cellosolve, and butyl-Cellosolve. Compounds known as Carbitols, which are alkyl ethers of diethylene glycol, such as the methyl-, ethyl-, propyl-, and butyl-Carbitols, the glycol and polyoxypolyalkylene glycol esters of low-mole wt. organic acids, such as acetates and propionates, may be used. These solvents may be used alone, in admixture, and in aqueous solution. The Udex extraction process described in the Petroleum Refiner, vol. 31, No. 9, Sept. 1952, p. 246, employing a diethylene glycol-water solvent containing about 2 to 10% of water, is the preferred method of separation and is used to illustrate the invention. The objectives of this step of this invention are met by using any of the foregoing or other known solvent-extraction process, and by using a solvent having a relatively high boiling point and low vapor pressure as compared with the aromatic and/or non-aromatic hydrocarbons in the reformat.

The alkylation reaction taking place in reactor 42 is carried out using conventional techniques. For this purpose, the desired ratio of saturated hydrocarbon entering line 36 and olefin hydrocarbon entering line 38 is contacted with an alkylation catalyst which may be sulfuric, phosphoric, or hydrofluoric acid, or any other agent having the property of promoting the alkylation reaction. The conditions of operation in alkylation unit 42 are well known and include temperatures in the range of about -10 to 90° F., using pressures in the order to 25 to 150 p.s.i.g., and about 0.05 to 0.2 mole of catalyst per mole of alkylation hydrocarbon mixture. The alkylation reaction, wherein saturated paraffinic hydrocarbons are combined directly with olefinic hydrocarbons to produce higher-molecular-weight hydrocarbons of a generally saturated character, is conducted in alkylation reactor 42. In the sulfuric acid alkylation process, which is used to illustrate the instant invention, a charge comprising one or more isoparaffinic hydrocarbons such as isobutane, and one or more olefinic hydrocarbons, including isobutylene, is contacted with sulfuric acid, generally concentrated sulfuric acid having a concentration of about 90% to 100%, at temperatures of 10° to 80° F., and at pressures up to 30 pounds per square inch. To prevent polymerization of the olefins, particularly when sulfuric acid is used as the catalyst, it is generally necessary to maintain a low concentration of olefinic reactant in the charge. The temperature used is limited by dealkylation and/or degradation of the hydrocarbon product to low-molecular-weight hydrocarbons and by the occurrence of side reactions, including polymerization of the olefinic reactant. This is particularly true where sulfuric acid is the catalyst. In

general, the acid catalyst such as sulfuric acid is used in an amount varying between about 10% and 100% by weight, based on the total weight of reactants charged at line 40.

Other alkylation processes, such as with the use of mercuric aluminum bromide or antimonous aluminum bromide at 750 pounds per square inch pressure and a temperature of 100 to 200° F., may be used. The technique of using boron fluoride promoted with methyl butene and water or hydrogen chloride may also be used. Similarly, aluminum chloride or a concentrated sulfuric acid catalyst containing a mercury compound and a selenium compound may be used.

One method that is applicable is described in U.S. Patent 2,435,761 wherein a C₄-C₇ paraffinic hydrocarbon such as isobutane is reacted with olefins such as butylenes using boron trifluoride promoted with chlorine or bromine. The employment of a gaseous mixture of isoparaffins and olefins with small particles of liquid hydrofluoric acid, at a temperature above the normal boiling point of hydrofluoric acid and at a pressure slightly above the critical pressure of the acid to allow its subsequent vaporization and consequent cooling of the reaction mixture, as described in U.S. Patent 2,437,544, may also be used. The catalyst may be bromine and carbon tetrachloride, carbon tetrabromide, chloroform, or bromoform in accordance with U.S. Patent 2,468,899. Regardless of the process applied in alkylation unit 42, the objectives of this invention will be obtained as long as the lower-boiling portion of the product in line 48 predominates in paraffinic hydrocarbons having 6 to 8 carbon atoms per molecule, and particularly if this alkylation product predominates in hexane or paraffins boiling in the hexane boiling range.

The last step of the process comprises a distillation carried out in still 50 designed to separate the alkylate as a bottoms fraction and the aromatic-free naphtha, as the primary product of this invention, is drawn off at line 54. In this process an overhead temperature of about 0° to 32° F. and pressures ranging from about 40 20 mm. to 740 mm. Hg are used. An overhead comprising unreacted paraffinic and olefinic hydrocarbons is removed by line 56 and recycled to line 40.

The spent acid withdrawn from line 46 is reconstituted by known methods and recycled to the alkylation unit.

Having thus described the invention with non-limiting examples the only limitations attaching thereto appear in the appended claims.

The embodiments of the invention in which an exclusive property or privilege is claimed are defined as follows:

1. The process of preparing paraffinic hydrocarbons boiling in the range of about 49° to 100° C., and having a content of aromatic hydrocarbons of less than about 0.5% by volume, which comprises reforming a naphtha rich in C₆ to C₈ paraffinic and naphthenic hydrocarbons to form a reformate, stabilizing the reformate, subjecting the stabilized reformate to solvent extraction using a solvent selective for the aromatic hydrocarbons present, recovering a raffinate phase rich in paraffinic hydrocarbons, subjecting said raffinate to alkylation in the presence of an alkylatable hydrocarbon mixture, and fractionating this resulting alkylated mixture to obtain at least one fraction boiling in the range of about 49° to 100° C. having a content of aromatic hydrocarbons of less than about 0.5% by volume.

2. The process of preparing paraffinic hydrocarbons boiling in the range of about 49° to 75° C. and having a content of aromatic hydrocarbons of less than about 0.5% by volume, which comprises reforming a naphtha rich in C₆ paraffinic and naphthenic hydrocarbons to form a reformate, stabilizing the reformate, subjecting the stabilized reformate to solvent extraction using a solvent selective for the aromatic hydrocarbons present,

recovering a raffinate phase rich in paraffinic hydrocarbons, subjecting said raffinate to alkylation in the presence of an alkylatable hydrocarbon mixture, and fractionating this resulting alkylated mixture to obtain at least one fraction boiling in the range of about 49° to 75° C. having a content of aromatic hydrocarbons of less than about 0.5% by volume.

3. The process of preparing paraffinic hydrocarbons boiling in the range of about 75° to 100° C., and having a content of aromatic hydrocarbons of less than about 0.5% by volume, which comprises reforming a naphtha rich in C₆-C₈ paraffinic and naphthenic hydrocarbons to form a reformate, stabilizing the reformate, subjecting the stabilized reformate to solvent extraction using a solvent selective for the aromatic hydrocarbons present, recovering a raffinate phase rich in paraffinic hydrocarbons, subjecting said raffinate to alkylation in the presence of an alkylatable hydrocarbon mixture, and fractionating this resulting alkylated mixture to obtain at least one fraction boiling in the range of about 75° to 100° C. having a content of aromatic hydrocarbons of less than about 0.5% by volume.

4. The process of preparing paraffinic hydrocarbons rich in hexane and boiling in the range of about 49° to 75° C., and having a content of aromatic hydrocarbons of less than about 0.5% by volume, which comprises reforming a naphtha rich in C₆ paraffinic and naphthenic hydrocarbons to form a reformate, stabilizing the reformate, subjecting the stabilized reformate to solvent extraction using a solvent selective for the aromatic hydrocarbons present, recovering a raffinate phase rich in paraffinic hydrocarbons, subjecting said raffinate to alkylation in the presence of an alkylatable hydrocarbon mixture, and fractionating this resulting alkylated mixture to obtain at least one fraction rich in hexane boiling in the range of about 49° to 75° C. having a content of aromatic hydrocarbons of less than about 0.5% by volume.

5. The process in accordance with claim 4 in which said recovered fraction predominates in hexane and contains about 0.38% by volume of benzene.

6. The process of preparing paraffinic hydrocarbons rich in heptane and boiling in the range of about 75° to 100° C., and having a content of aromatic hydrocarbons of less than about 0.5% by volume, which comprises reforming a naphtha rich in C₇ paraffinic and naphthenic hydrocarbons to form a reformate, stabilizing the reformate, subjecting the stabilized reformate to solvent extraction using a solvent selective for the aromatic hydrocarbons present, recovering a raffinate phase rich in paraffinic hydrocarbons, subjecting said raffinate to alkylation in the presence of an alkylatable hydrocarbon mixture, and fractionating this resulting alkylated mixture to obtain at least one fraction rich in heptane boiling in the range of about 75° to 100° C. having a content of aromatic hydrocarbons of less than about 0.5% by volume.

7. The process in accordance with claim 5 in which said recovered fraction predominates in heptane and contains about 0.24% by volume of toluene.

8. The process of preparing paraffinic hydrocarbons boiling in the range of about 49° to 75° C. and having a content of aromatic hydrocarbons of less than about 0.5% by volume, which comprises reforming a naphtha rich in C₆ paraffinic and naphthenic hydrocarbons at a temperature of about 70° to 1050° F. and a pressure of about 150 to 1000 p.s.i.g. in the presence of a platinum-containing catalyst to form a reformate, stabilizing the reformate, subjecting the stabilized reformate to contact with a solvent comprising diethylene glycol and water, separating a raffinate phase rich in paraffinic hydrocarbons, subjecting said raffinate to alkylation in the presence of concentrated sulfuric acid and an alkylatable hydrocarbon mixture comprising isobutylene and isobutane to produce an alkylate reaction product, and frac-

tionating the alkylate reaction product to obtain at least one fraction boiling at about 68° C. comprising substantially pure hexane and having a content of aromatic hydrocarbons of less than about 0.5% by volume.

9. The process of preparing paraffinic hydrocarbons boiling in the range of about 75° to 100° C., and having a content of aromatic hydrocarbons of less than about 0.5% by volume, which comprises reforming a naphtha rich in C₇ paraffinic and naphthenic hydrocarbons at a temperature of about 70° to 1050° F. and a pressure of about 150 to 1000 p.s.i.g. in the presence of a platinum-containing catalyst to form a reformate, stabilizing the reformate, subjecting the stabilized reformate to contact with a solvent comprising diethylene glycol and water, separating a raffinate phase rich in paraffinic hydrocar-

10
5 bons, subjecting said raffinate to alkylation in the presence of concentrated sulfuric acid and an alkylatable hydrocarbon mixture comprising isobutylene and isobutane to produce an alkylate reaction product, and fractionating the alkylate reaction product to obtain at least one fraction boiling at about 100° C. comprising substantially pure heptane and having a content of aromatic hydrocarbons of less than about 0.5% by volume.
